EDWARD E. HINRICHSEN, OF ALEXANDER, ILLINOIS, AND JOHN F. TOOMEY, OF NEW YORK, N. Y., ASSIGNORS TO WESTERN ELECTRIC COMPANY, OF NEW YORK, N. Y., A CORPORATION OF ILLINOIS.

TOLL OPERATING-CIRCUITS.

1,097,861.

Specification of Letters Patent.

Patented May 26, 1914.

Application filed November 18, 1911. Serial No. 660,988.

To all whom it may concern:

Be it known that we, EDWARD E. HINRICHSEN and JOHN F. TOOMEY, citizens of the United States, residing, respectively, at 5 Alexander, in the county of Morgan and State of Illinois, and at New York, in the county of New York and State of New York, have invented a certain new and useful Improvement in Toll Operating-Circuits, 10 of which the following is a full, clear, concise, and exact description.

This invention relates to a telephone switching system in which the connection between calling and called lines is made 15 through two trunking lines in series or tandem, and more particularly to a toll trunk line adapted for connection with a type of switching trunk which is itself adapted to be used without change either in connection 20 with a toll cord circuit or with a machine ringing trunk. The toll trunk line will for convenience be referred to hereinafter as the tandem trunk and it is the object of this 25 invention to provide a tandem trunk so equipped as to facilitate the connections between the calling and called line by reducing to a minimum the number of operations of the trunking operators in setting up the 30 connections, this being accomplished by having the signaling of the called party and the supervision features for the most part automatic and under control of the calling operator.

One of the features of this invention relates to the organization of the apparatus in 35 the tandem trunk for automatically connecting ringing current with the called line when all manual switching connections are completed. This feature consists essentially 40 in associating electromagnetic switching apparatus, comprising a plurality of relays, with the tandem trunk, the relation of said relays to each other and to the tandem trunk being such that they are controlled jointly 45 by the several switching operations necessary to connect the lines, said electromagnetic switching apparatus in turn controlling the application of ringing current to the 50 called line.

Another feature of this invention relates 55 to the organization of the apparatus in the tandem trunk, whereby the disconnection

and reconnection of the calling operator's cord circuit with the tandem trunk will cause a second application of the ringing 55 current to the called line when the tandem trunk is connected with a switching trunk and the called party of the line with which the switching trunk is connected has disconnected his telephone therefrom. This 60 feature consists in so grouping and connecting a number of relays with the trunk circuit that certain ones of them which were operated to start the ringing initially are released by the disconnection of the 65 called party's telephone and the withdrawal of the calling plug from the tandem toll trunk, these relays which are thus released being again operated by conditions caused by the reinsertion of the calling plug to 70 again connect ringing current with the called line. The controlling circuit for the operation of the electromagnetic switching means may be a local circuit controlled by a relay associated with the tandem trunk, or 75 may be the one closed in the initial operation of these relays, depending upon whether the switching trunk is connected with a subscriber's line or with a private branch exchange switchboard.

A third feature of this invention relates to the association of apparatus with the tandem toll trunk, whereby the calling operator obtains supervision of the connection as soon as the called party answers the call. Specifically this feature consists in the provision 80 in connection with the tandem trunk of a relay associated with the outgoing end thereof and controlling the operation of the supervisory relay in response to circuit conditions controlled by the connection and disconnection of the called party's telephone with the called line. This controlling relay is normally in series with a high resistance winding of a second relay having also a 85 low resistance winding adapted to be connected in parallel with its high resistance winding by a third relay associated with said tandem trunk and operating when the called subscriber connects his telephone with 90 the line.

Other features of this invention are the details of apparatus and circuits which will be more fully described hereinafter.

In the drawings—Figure 1 represents a subscriber set, a line circuit therefor terminating in a local office and the circuit wiring of the apparatus at the local office. Fig. 2 represents the apparatus at a trunk office wired in accordance with this invention and adapted for connection with the circuits of Fig. 1; and Fig. 3 represents the circuit wiring of the apparatus at a local station to which a toll trunk is adapted to be connected including the cord and line circuits and a subscriber set circuit.

The three figures when placed together end to end are adapted to form a continuous connecting circuit from a subscriber at one end of the toll line to a subscriber at the opposite end of said toll line. In the accompanying description of the operation of this invention, it will be assumed for the sake of convenience and clearness that the apparatus shown on Fig. 3 is located at San Francisco, that shown in Figs. 1 and 2 being located at Oakland.

The subscriber set circuits, line circuit and cord circuit shown are all well known in the art and need not be described in detail. Aside from the removal of the subscriber's receiver from the switch hook, there are four switching operations necessary. These are the connection of cord circuit 8 with the calling line through a plug 7 and jack 9, the connection of the cord circuit 8 with the outgoing end of a tandem trunk 100 through a plug 22 and jack 25, the connection of the tandem trunk 100 with a switching trunk 200 through a plug 201 and a jack 202 and the connection of the switching trunk 200 with called subscriber's line through plug 300 and jack 301. The tip and ring springs of jack 25 at the outgoing end of the tandem trunk 100 are connected with windings 30, 30 of a repeating coil 31, the windings 30, 30 being separated by a condenser 32 and located in inductive relation to windings 33, 33 of the repeating coil 31, which latter windings are separated by a condenser 34. The repeating coil 31 is located at the San Francisco local exchange and the windings 33, 33 thereof are adapted to be connected with windings 250, 250 of a repeating coil 251 at the Oakland toll office. Said windings 250, 250 are separated by a condenser 252 and are located in inductive relation to windings 253, 253 of the repeating coil 251, which windings are separated by a condenser 254. The tip and ring contacts of the jack 202 of the switching trunk are connected with windings 350, 350 of a third repeating coil 351 located at the Oakland local exchange, said windings 350, 350 being separated by a condenser 352 and located in inductive relation to windings 353, 353 of said repeating coil 351, which latter windings are separated by a condenser 354. The repeating coils 31 and 351 are inserted in the

line for talking purposes while the repeating coil 251 is used for signaling purposes.

The invention may be best described by following the operation of the circuits and apparatus during the setting up of a connection between a subscriber in one town, say San Francisco, and a subscriber in another town, say Oakland. Assuming then that a subscriber A at San Francisco desires to converse with a subscriber B at Oakland, subscriber A will remove the receiver 1 from the switch hook 2, thus completing a circuit over the two line wires 3 and 4 through a line relay 5. The operation of the line relay 5 will light line lamp 6 and thus indicate to the local operator at the particular exchange in San Francisco with which the calling subscriber is connected, that such subscriber is calling. The local exchange operator responds to the signal of the line lamp by inserting an answering plug 7 of the cord circuit 8 into a line jack 9 and depressing a key 10 which connects her telephone set 12 with the tip and ring wires 13 and 14 of the cord circuit. The insertion of the plug 7 into the jack 9 completes a circuit from battery 20 through a supervisory lamp 15, the sleeve contacts of the plug and jack 7 and 9 and a cut-off relay 16 to ground. Sufficient current will flow in this circuit to light the supervisory lamp 15 and operate the cut-off relay 16, the operation of the cut-off relay opening the circuit of the line relay 5 and extinguishing the line lamp 6. The insertion of the plug 7 into the jack 9 will also complete a circuit through a supervisory relay 17, the operation of which shunts the supervisory lamp 15 with a low resistance 18. This will extinguish the lamp 15, but will retain the cut-off relay 16 energized. The local operator at San Francisco upon determining that party A desires to talk with party B at Oakland, so advises the toll operator at Oakland over an order wire circuit which is not shown as it is not a part of this invention and is well enough known in the art to require no description here. The toll operator at Oakland assigns a trunk line to the local operator at San Francisco, which is the one terminating in jack 25 in front of said local operator. At the same time the toll operator at Oakland will get into communication over an order wire circuit with the switching operator at the Oakland exchange with which the line of the desired party connects. The switching exchange operator then assigns a trunk to the Oakland toll operator and inserts the plug 300 of that trunk into a jack 301 in which the line of party B terminates. Upon receiving the trunk assignment from the Oakland switching operator, the Oakland toll operator inserts the plug 201 of the trunk she assigned the San Francisco local operator into the jack 202 of the as-

signed trunk between Oakland toll and Oakland local. The assignment of trunks and setting up of the connections is the only operation necessary on the part of the Oakland operators until the conversation has been completed and disconnection is made, the remainder of the operations being for the most part automatic and controlled by the San Francisco local operator and the subscribers.

10 Assuming now that the manual switching connections have all been established, the succeeding operations for completing the signaling circuit and signaling will be as follows: Upon the insertion of the plug 22 into the jack 25 at the outgoing end of the tandem trunk, a circuit will be completed from battery 20 through supervisory lamp 26, resistance 27, sleeve contacts of the plug 22 and jack 25, conductor 312 and winding of relay 28 to ground. Current in this path will energize the relay 28, closing front contacts 29, 29 and connecting conductors 35, 35 with line conductors 36, 36 which are connected with the windings 250, 250 of the repeating coil 251 at the toll trunk office in Oakland. This completes a circuit from battery 20 through one winding of a relay 37, conductor 38, one winding 33 of repeating coil 31, conductor 35, one contact 29 of relay 28, the corresponding line conductor 36, one winding 250 of repeating coil 251, conductors 39 and 40, a high resistance winding 41 on a relay 42, conductor 43, the other winding 250 of the repeating coil 251, corresponding line conductor 36, the other contact 29 of the relay 28, conductor 35, the other winding 33 of the repeating coil 31, conductor 44 and the other winding of the relay 37 to ground. Current over this path energizes 40 the relay 42 through its winding 41, but owing to the high resistance of said winding 41 insufficient current will flow to energize relay 37. The operation of relay 42 closes its front contact 45 and completes a circuit for a relay 50 which may be traced from battery 51 through winding of relay 50, conductor 52, conductor 53 and front contact 45 of relay 42 to ground. Current in this path operates the relay 50 to close contacts 54 and 55 and open contact 56 and will complete a circuit for lighting a lamp 58. This circuit may be traced from battery 51 at the plug end of the tandem trunk, conductor 59, normally closed contact 60 of a relay 51, conductor 62, contact 54 of relay 50, conductor 63 and lamp 58 to ground. The lighting of the lamp 58 will indicate to the toll operator that the San Francisco local operator has plugged into the proper trunk.

55 When the tandem trunk operator inserts the plug 201 into the jack 202 of the switching trunk the relay 61 will be energized by current in a circuit traced from the battery 51, winding of relay 61, conductor 65, sleeve contacts of the plug and jack 201 and 202

through resistance coil 66 to ground. The operation of the relay 61 will open the contact 60, thus interrupting the circuit for the lamp 58 previously traced and will close contacts 67 and 68. Aside from the relays 42, 50 and 61 already mentioned, there are associated with the tandem trunk at the incoming end thereof relays 70, 71, 72, 73, 74, 75, 76, 77 and 78, which, in conjunction with relays 80, 81, 82, 83, 84, 85, 86, 87, 88 and 89 associated with the connecting trunk, operate in the sequence of their numbers in the separate circuits to ring the called subscriber and give the proper disconnect signals when the conversation is completed. The relay 86 serves as an electromagnetic ringing key to connect ringing current with the called line. Referring first to the means for signaling the called subscriber, the operation will be as follows: After the operation of the relays 50 and 61 hereinbefore referred to, there will be completed a circuit for the relay 70 which may be traced as follows: from battery 90 at the Oakland local exchange through one winding 91 of the relay 80, conductor 92, normally closed contact 93 of relay 81, conductor 94, conductor 95, one winding 350 of repeating coil 351, conductor 96, ring contacts of jack and plug 202 and 201, conductor 97, normally closed contact 98 of the relay 76, conductor 99, one winding 253 of the repeating coil 251, conductor 102, conductor 103, contact 55 of relay 50, conductor 104, back contact 105 of the relay 71, conductor 106, winding of relay 70, conductor 107, conductor 108, the other winding 253 of repeating coil 251, conductor 109, normally closed contact 110 of the relay 76, conductor 111, contact 68 of relay 61, conductor 112, tip contacts of the plug and jack 201 and 202, conductor 113, the other winding 350 of repeating coil 351, conductor 114, normally closed contact 115 of relay 81, conductor 116 and through winding 117 of relay 80. The current in this path will energize both relays 70 and 80. The operation of relay 70 closes its front contact 120 and completes circuits for relays 71 and 72. The circuit for relay 71 will be from battery 51 through winding of relay 71, conductor 121, conductor 122, front contact 120 of the relay 70, conductor 123, conductor 53 and front contact 45 of relay 42 to ground. The circuit for the relay 72 will be from battery 51, through one winding 125 of the relay 72, conductor 126 to point 127, conductor 128, normally closed contact 129 of relay 74, conductor 313, conductor 122, front contact 120 of relay 70, conductor 123, conductor 53, front contact 45 of relay 42 to ground. When relay 71 operates, it opens back contact 105 and closes contacts 130 and 131. With the closing of contact 131 a locking circuit is completed for relay 71 which may be traced from battery 51 through the wind-

ing of relay 71, conductor 121, contact 131, conductor 132, conductor 53, contact 45 of relay 42 to ground. The operation of relay 72 will close its front contact 133 which is connected through conductor 134 with one terminal of the winding of the relay 76, the other terminal of which is connected to ground. There will be no current through this relay, however, inasmuch as the point 127 is at this time ground potential. The closing of the contact 130 of the relay 71 will connect the relay 73 with the line wires 99 and 109 in shunt of the condenser 254, the circuit being as follows: from line 109 at one side of the condenser 254, conductor 108, conductor 135, winding of relay 73, conductor 136, contact 130 of relay 71, conductor 104, contact 55 of relay 50, conductor 103 and conductor 102 to the line 99 at the other side of the condenser 254. This prepares a path through the winding of the relay 73 over which current may flow from the switching trunk as will be hereinafter explained.

Referring now to the sequence of operations of the relays in the switching trunk, it will be noted that when the relay 80 operates, it opens a back contact 140 and closes a front contact 141. The closing of the front contact 141 completes a circuit from the 48 volt battery 145, contact 141, conductor 146 through one winding 147 of relay 81, conductor 148, normally closed contact 149 of the relay 83, lamp 150 to the battery 90. The battery 90 being a 24 volt one, there will be a pressure of 24 volts over this circuit, which will energize the relay 81 and light the lamp 150. The operation of relay 81 will open contacts 93 and 115 and close contacts 152 and 153. The opening of contacts 93 and 115 opens the circuit over which relay 70 was originally energized, while the closure of contacts 152 and 153 completes a local circuit for the relay 80 through a resistance 154. When the plug 300 is in the jack 301, there will be a circuit for relays 82 and 83 which may be traced from battery at 90, winding of relay 82, conductor 160, winding of relay 83, conductor 161, sleeve contacts of plug 300 and jack 301, conductor 162 and cut-off relay 163 to ground. The current in this path will energize relays 82 and 83. The operation of relay 82 will open its back contact 165 and close its front contact 166, which is connected with a conductor 167 leading to a ringing generator 168. This will have no effect, however, as the path for ringing current is open at another point which is not closed until later. The operation of relay 83 opens contact 149 and closes contacts 170 and 171. The opening of contact 149 opens the energizing circuit for relay 81, thus opening the contacts 152 and 153 and closing contacts 93 and 115. The closing of contact 170, however, completes a circuit for relay 84 which may be traced from the 48-volt battery 145 through winding of relay 84, conductor 172, conductor 173, contact 170 of relay 83, the lamp 150 and the 24 volt battery 90 to ground. This will operate the relay 84, but on account of said relay being of high resistance will not light the lamp 150. The contacts 93 and 115 of relay 81 being again closed, there will be a flow of current through the windings of the relay 80 and back to the tandem trunk over practically the same path that it took when relay 70 was energized, except that this time, instead of going through the back contact of relay 71 and conductor 106 to the winding of relay 70, it will pass through front contact 130 of relay 71, conductor 136, winding of relay 73, conductor 135 and from there back to ground, the remainder of the path being the same as previously traced for relay 70. The current in this path will energize the relays 73 and 80, the local circuit of relay 80 through the resistance 154 having been opened by the opening of the contacts 152 and 153 when relay 83 pulled up and opened the circuit of relay 81. The operation of relay 73 closes front contact 176 and completes an energizing circuit for relays 74 and 75, which circuit may be traced from battery 51 through winding 177 of relay 75, conductor 178, winding of relay 74, conductor 179, conductor 180, front contact 176 of relay 73, conductor 181, back contact 182 of relay 70, conductor 123, conductor 53 and front contact 45 of relay 42 to ground. The current in this path causes the operation of relays 74 and 75. The operation of relay 74 opens contacts 129 and 183 and closes contact 184, completing a locking circuit for the relays 74 and 75, which may be traced from battery 51, winding 177 of relay 75, conductor 178, winding of relay 74, conductor 179, contact 184, conductor 185, conductor 53, contact 45 of relay 42 to ground. The operation of relay 75 closes contacts 186 and 187 and completes a locking circuit for itself through winding 190 thereof, this circuit being traced from battery 51, conductor 59, contact 67 of relay 61, conductor 191, contact 187 of relay 75, conductor 192, winding 190 of relay 75 and conductor 193 to ground.

The opening of contact 129 of the relay 74 will remove the ground from conductor 128 and cause the current to flow through both windings of the relay 72, contact 133, conductor 134 and winding of relay 76 to ground. This will be but an impulse, however, as the two windings of the relay 72 are connected differentially and this relay will be released by this flow of current, not, however, before the operation of the relay 76.

When the relay 76 operates, it opens contacts 98 and 110, closing contacts 205 and 131

206 and completing an energizing circuit from generator 207 for the relay 85 at Oakland switching exchange. This circuit may be traced from generator 207, conductor 208, 5 lamp 209, conductor 210, contact 205 of relay 76, conductor 97, ring contacts of plug 201 and jack 202, conductor 96, one winding 350 of repeating coil 351, conductor 95, condenser 211, winding of relay 85, conductor 212, the other winding 350 of repeating coil 351, conductor 113, tip contacts of jack 202 and plug 201, conductor 112, contact 68 of relay 61, conductor 111 and contact 206 of relay 76 to ground. The operation of relay 10 85 closes its front contact 215 and completes an energizing circuit for relays 88, 87, 86 and 81 in series, which circuit may be traced as follows: from battery 90, conductor 216, winding of relay 88, conductor 217, winding 20 of relay 87, conductor 218, winding 219 of relay 86, conductor 220, contact 215 of relay 85, conductor 222, through winding 223 of relay 81 to ground. Current in this circuit operates relays 88, 86, 87 and 81. The operation of relay 88 closes a locking circuit for the relays 86, 87 and 88, which may be traced from battery 90, conductor 216, winding of relay 88, conductor 217, winding of relay 87, conductor 218, winding 225 of relay 30 86, conductor 226, contact 227 of relay 88, conductor 228, conductor 229, back contact 230 of relay 89, conductor 231 and contact 232 of relay 84 to ground. This circuit remains closed until opened at the back contact 230 of relay 89 as will later appear. When the relay 86 operates, a circuit is completed from the ringing generator 168 through a bell 236 at the subscriber's station B. This circuit may be traced from generator 40 168, conductor 167, front contact 166 of relay 82, conductor 239, winding of relay 89, conductor 240, front contact 241 of relay 86, conductor 242, ring contacts of plug 300 and jack 301, line wire 243, bell 236, condenser 244, line wire 245, tip contacts of jack 301 and plug 300, conductor 246, front contact 171 of relay 83, conductor 264, and front contact 247 of relay 86 to ground. The current in this circuit will ring the bell 236, but 45 owing to the high impedance of the bell magnets will not operate the relay 89 as long as the switch hook at subscriber station B remains on the hook. When the subscriber at station B answers the ring, however, the operation of the receiver switch hook shunts the bell 236 and the current through this shunt path will be sufficient to energize the relay 89 to open the contact 230 thereof. The opening of the contact 230 interrupts the 50 holding circuit of relays 86, 87 and 88. When relay 86 is deenergized, it opens front contacts 241 and 247 and closes back contacts 255 and 256, thus interrupting the ringing circuit and completing the talking circuit over the switching trunk.

Referring now to the supervisory features of this system, it will be noted that the second energization of relay 81, which occurs upon the closure of contact 215 of relay 85, is only momentary and closes only for an instant the local circuit of the relay 80. This relay 80 is made slow-releasing by means of a copper shell over the core, and although 81 falls back almost immediately, there will be a short period of time intervene before relay 80 drops back. During this intervening time, however, the relay 76 will have been deenergized, thus closing contacts 98 and 110 and completing the original energizing circuit of the relay 80 in series with the relay 73 in the tandem trunk until the relay 81 is again energized. The third energization of relay 81 occurs when the party at station B removes his receiver from the hook for the purpose of answering the call. When this occurs an energizing circuit is completed from the 48 volt battery 145, through contact 141 of relay 80, conductor 146, winding 147 of relay 81, conductor 257, one winding 353 of repeating coil 351, conductor 258, contact 256 of relay 86, conductor 242, ring contacts of plug 300 and jack 301, line wire 243, primary 259 of induction coil 260, contact 261 of switch hook 262, transmitter 263, line wire 245, tip contacts of jack 301 and plug 300, conductor 246, contact 171 of relay 83, conductor 264, contact 255 of relay 86, conductor 265, the other winding 353 of repeating coil 351, conductor 222 and winding 223 of relay 81 to ground. The operation of relay 81 by current over this path opens contacts 93 and 115, thus interrupting the circuit through the relay 73 of the tandem trunk.

When relay 73 is deenergized, it will close its back contact 270 and complete a circuit for the relay 77 which may be traced as follows: from battery 51 at the plug end of the tandem trunk, conductor 59, contact 67, conductor 191, conductor 271, contact 186 of relay 75, conductor 272, conductor 273, winding of relay 77, conductor 274, back contact 270 of relay 73, conductor 181, back contact 182 of relay 70, conductor 123, conductor 53 and contact 45 of relay 42 to ground. The operation of relay 77 closes its front contact 276 connecting conductors 277 and 278 together and thus placing the low resistance winding 279 of the relay 42 in parallel with the high resistance winding 41 thereof. With these two windings in parallel, there will be sufficient current flow through the relay 37 at the outgoing end of the tandem trunk to energize said relay 37. The operation of the relay 37 closes its front contact 285 and completes a circuit for the supervisory relay 19 in the cord circuit. This circuit may be traced from the bridged battery 20 in the cord circuit through conductor 14, 180

the winding of the relay 19, conductor 286, closed key contacts 287, 287, ring contacts of plug 22 and jack 25, conductor 288, one winding 30 of repeating coil 31, conductor 290 including resistance 291, contact 285, conductor 292, the other winding 30 of repeating coil 31, conductor 293, tip contacts of jack 25 and plug 22, key contacts 294, 294, and conductor 13 to the ground side 5 of the bridge battery 20. This operates the 10 supervisory relay 19, closing contact 295 and shunting lamp 26 with low resistance 296, thereby causing said lamp to be extinguished and indicating to the local operator at San Francisco that the called 15 party at Oakland has answered. Assuming now that the subscriber at Oakland hangs up his receiver either at the completion of the conversation or for any other reason, 20 this will be indicated at the San Francisco local exchange by the illumination of the supervisory lamp 26 through the following operation of the circuit apparatus. The hanging up of the receiver at subscriber 25 station B will open the contact 261, thus interrupting the energizing circuit last traced for the relay 81. The deenergizing of this relay will close the contacts 93 and 115, thus closing the energizing circuit for 30 the relay 73 hereinbefore traced. The operation of the relay 73 opens contact 270, interrupting the circuit of the relay 77 and opening contact 276 of said relay 77. The opening of contact 276 takes the low resistance winding 279 of relay 42 out of 35 the energizing circuit of the relay 37 at the outgoing end of the tandem trunk, thus increasing the resistance of this circuit to such an extent that said relay 37 falls back 40 and opens its contact 285. The opening of contact 285 interrupts the circuit of the supervisory relay 19 which in turn interrupts the circuit of the shunt resistance 296 and permits the lamp 26 to light. If 45 now the San Francisco operator desires to re-ring the Oakland subscriber, she does so by withdrawing plug 22 from the jack 25 and re-inserting it. The withdrawal of the plug 22 from the jack 25 releases relays 50 28, 42, 50, 71, 73 and 74 in the tandem trunk and relay 80 of the switching trunk. The re-insertion of plug 22 into the jack 25 operates the relays in the sequence described in the operation of the system to 55 again ring the subscriber at station B.

The switching trunk 200 is adapted for connection with a private branch exchange trunk as well as with a subscriber's line. When the switching trunk 200 is connected 60 with a private branch exchange trunk, there will be a holding coil across the line at the private branch exchange which will prevent the release of the relay 81 when the called subscriber hangs up his receiver. 65 The relay 81 remaining energized, will pre-

vent the closing of the contacts 93 and 115 and the consequent energization of relay 70 by current in the path originally traced for the energization of this relay. It will be seen, therefore, that in order to trip the 70 ringing by withdrawing and re-inserting the plug 22 into the jack 25, there must be some other source of current for energizing the relay 70 than that provided by the battery 90 of the switching trunk at 75 the Oakland local office. This is provided for by the relay 78 at the incoming end of the tandem trunk 100 at Oakland toll office.

The operation of the apparatus upon a 80 re-ring will under these conditions be as follows: When the operator at San Francisco re-inserts plug 22 into the jack 25, the relay 28 will operate, completing the circuit for the relay 42. The operation of relay 85 42 will complete the energizing circuit for relay 50 and also for the relay 78, the latter circuit being traced from battery 51 at the plug end of the tandem trunk through conductor 59, contact 67 of relay 61 which was 90 not released by the withdrawal of plug 22 from jack 25, conductor 191, conductor 271, contact 186 of relay 75, conductor 272, conductor 306, winding of relay 78, conductor 307, contact 183 of relay 74, conductor 185, 95 conductor 53 and contact 45 of relay 42 to ground. Current in this path will energize the relay 78 and close contacts 308 and 309 thereof. The closure of contacts 308 and 309 completes a circuit for the relay 70 which may be traced from battery 51, 100 through contact 308 of relay 78, conductor 310, conductor 107, winding of relay 70, conductor 106, back contact 105 of relay 71, conductor 104, contact 55 of relay 50, conductor 103, conductor 311 and contact 309 of relay 78 to ground. The current in this path will energize relay 70 and the relays of the tandem trunk and switching trunk will operate in the sequence and over the 110 circuits originally traced to start the ringing and signal the private branch exchange operator.

The relay 70 is provided with a copper head 325 which makes this relay slow-acting 115 the purpose of this being to prevent the energization of the relay 73 in case the toll operator plugs into the jack 202 before the switching operator has made connections with the called subscriber's line. As will 120 be noted from the drawings the insertion of the plug 201 into the jack 202 will cause an impulse of current to flow from the battery 90 at the switching trunk back over the line and through the relay 70. This impulse is only for an instant, however, and will suffice to operate the relay 70, but the relay 81 will have operated before the relays 71 and 72 have closed their front contacts, thereby removing the battery 90 from 125 130

the line before the relay 73 is brought into circuit therewith.

The switching trunk shown in Fig. 1 is arranged for connection with lines in which the party is called by either one or two rings and is adapted to automatically take care of these two classes of ringing. For this purpose there is provided in addition to the relay 82 a second relay 330 which is dependent for its operation upon the non-operation of the relay 82. If there is no resistance other than that of the cut-off relay 163 in the sleeve wire 162 of the jack 301 then the relay 82 will be operated upon the connection of the plug and jack 300 and 301 and the ringing current will have the path previously traced. If, however, the plug 300 is inserted into a jack 301 in which there is additional resistance in the sleeve wire 162, the relay 82 will not be operated and a circuit will be closed for the relay 330 upon the operation of the relays 85, 86, 87 and 88. The operation of relay 330 will close a path for interrupted ringing current which will be through the back contact of the relay 82 and over the path previously traced. This forms no part of the invention, however, and the specific operation and circuits need not be herein traced.

30 When the plugs are removed from the jacks in making disconnection, the relays will all return to their normal or unoperated position preparatory to another call.

While this invention has been described in connection with a particular class of toll line business, it is to be understood that the invention is not limited to this particular class, but may be applied to any class of toll business, although not recommended for use 40 in connection with lines of too great length on account of the cost of installation.

We claim:

1. The combination with telephone trunk lines and connecting switches at each terminal of each of said trunk lines uniting said trunk lines with each other and with other lines, of an electromagnetic ringing key associated with one of said trunk lines, an energizing circuit for said ringing key and means in each of said trunks controlled jointly by the connection switches at the terminals of said trunk lines for closing the circuit for said ringing key.

2. The combination with telephone trunk lines and connecting switches at each terminal of each of said trunk lines uniting said trunk lines with each other and with other lines, of an electromagnetic ringing key associated with one of said trunk lines, electromagnetic switching means associated with the other of said trunk lines controlling the operation of said ringing key, said electromagnetic switching means being under the joint control of the connection switches at both ends of said trunk lines.

3. The combination with telephone trunk lines and connection switches at each terminal of each of said trunk lines uniting said trunk lines with each other and with other lines, an electromagnetic ringing key 70 associated with one of said trunk lines, a relay associated with said trunk line controlling the operation of said ringing key, a source of alternating current and electromagnetic switching means associated with the other of said trunk lines and operating under the joint control of the connecting switches at the ends of said trunk lines to close a circuit for said relay including said alternating current source. 80

4. The combination with a calling and a called line, of a telephone switching trunk line, a tandem trunk line, connection switches at each terminal of said trunk lines for uniting them with each other and with the calling and called lines, an electromagnetic ringing key associated with said switching trunk line, electromagnetic means comprising a plurality of relays associated with each of said trunk lines and controlling the operation of said ringing key, a circuit controlling certain ones only of said relays completed by the connection switches uniting said tandem trunk with the calling line and with said switching trunk and a 95 circuit controlling the operation of the remaining ones of said relays controlled by the connection switches uniting the switching trunk with the called line.

5. The combination with a calling and 100 a called line, of a switching trunk line, a tandem trunk line, connection switches at each terminal of said trunk lines uniting them with each other and with the called and calling lines, respectively, an electromagnetic ringing key associated with said switching trunk, electromagnetic switching means comprising a plurality of relays controlling the operation of said ringing key, a slow-acting relay included in said 110 electromagnetic switching means and controlling the operation of certain ones only of said relays, a circuit for said slow-acting relay under the joint control of the connection switches uniting said tandem trunk 115 with the calling line and with the switching trunk, a second relay included in said electromagnetic switching means and controlling the operation of the remaining ones of said relays, and a circuit for said second relay 120 under the joint control of the said slow-acting relay and the connection switches uniting the switching trunk with the called line.

6. The combination with trunking lines, a cord circuit and a called line, of connection switches for uniting said trunk lines with each other and with said cord circuit and called line, a supervisory signal associated with said cord circuit and means in each of said trunk lines for controlling the 130

- 8
11. The combination with telephone trunk lines and connecting switches at each terminal of each of said lines uniting said trunk lines with each other and with other lines, of an electromagnetic ringing key associated with one of said trunk lines, an energizing circuit for said ringing key, means in each of said trunks controlled by the joint action of the connection switches at the terminals of said trunk lines for closing said energizing circuit, means for opening the circuit of said key, a circuit controlling said key circuit opening means completed over one of said lines, and means controlled by a second operation of the connection switches at one terminal of one of said trunk lines for again operating the circuit closing means of said ringing key. 70
12. The combination with telephone trunk lines and connection switches at each terminal of each of said trunk lines for uniting them with each other and with other lines, of an electromagnetic ringing key associated with one of said trunk lines, an energizing circuit for said ringing key, electromagnetic switching means associated with each of said trunk lines controlling the circuit of said ringing key, said electromagnetic switching means operating under the joint control of all of said connection switches, means for opening the circuit of said ringing key, a circuit for said circuit opening means completed over one of the lines with which said trunks are connected, and means controlled by a second operation of the connection switches at one terminal of one of said trunk lines for again operating said electromagnetic switching key. 85 90
13. The combination with a switching trunk line, a tandem trunk line, a connecting cord circuit and a called line, of connection switches uniting said trunk lines with each other and with said cord circuit and a called line, a ringing key associated with said switching trunk, means associated with said tandem trunk operated by said connection switches controlling an energizing circuit for said key, means for releasing said key, a circuit for said releasing means controlled over the called line, and means controlled by the connection switch uniting the tandem trunk and the cord circuit for again closing the energizing circuit of said ringing key. 105 110 115
14. The combination with a switching trunk line, a tandem trunk line, a cord circuit and a called line, of connection switches uniting said trunk lines with each other and with said cord circuit and called line, an electromagnetic ringing key associated with said switching trunk line, electromagnetic switching means associated with each of said trunk lines and operating under the joint control of all of said connection switches to operate said ringing key, means for releasing said ringing key, a circuit for said re- 120 125 130

7. The combination with telephone trunking lines, a connecting cord circuit and a called line, of connection switches for uniting said trunk lines with each other, with said cord circuit and with said called line, a supervisory relay associated with said cord circuit, electromagnetic switching means in each of said trunk lines controlling the operation of said supervisory signal, and a circuit controlling the operation of said electromagnetic switching means established over the called line. 75
8. The combination with a called line, a connecting cord circuit and switching and tandem trunks for uniting said called line and said cord circuit, of a supervisory signal associated with said cord circuit, a relay associated with the outgoing end of said tandem trunk controlling the circuit of said supervisory signal, electromagnetic switching means in each of said trunk lines controlling the operation of said relay and a circuit controlling the operation of said electromagnetic switching means completed over the called line. 80
9. The combination with a called line, a connecting cord circuit, and switching and tandem trunk lines for uniting said called line and said cord circuit, of a supervisory relay associated with said cord circuit, a relay associated with said tandem trunk controlling the operation of said supervisory relay, a second relay having a high and low resistance winding, a circuit for said controlling relay including the high resistance winding of said second relay, electromagnetic switching means for connecting the high and low resistance windings of said second relay in parallel, and a controlling circuit for said switching means completed over the wires of said called line. 95
10. The combination with a called line, a connecting cord circuit and switching and tandem trunk lines for uniting said cord circuit and said called line, of a supervisory relay associated with said cord circuit, a relay associated with the outgoing end of said tandem trunk for controlling the operation of said supervisory relay, a second relay associated with said tandem trunk and having a high resistance winding and a low resistance winding, a circuit for said controlling relay including the high resistance winding of said second relay, a third relay associated with said tandem trunk adapted to connect the high and low resistance windings of said second relay in parallel, a relay associated with said switching trunk controlling the operation of said third named relay, and a circuit for said switching trunk relay completed over said called line. 100 105 110 115 120 125 130

leasing means controlled over the called line, and means controlled by the connection switches uniting said tandem trunk line and said cord circuit for again operating said electromagnetic switching means.

15. The combination with a switching trunk line, a tandem trunk line, a connecting cord circuit and a called line, of connecting switches uniting said trunk lines with each other and with said cord circuit and said called line, a ringing key associated with said switching trunk, electromagnetic switching means associated with said tandem trunk controlling said ringing key, said connecting

switches controlling said electromagnetic 15 switching means.

In witness whereof, we hereunto subscribe our names this 15th day of November, A. D., 1911.
